UNITED STATES PATENT OFFICE.

CHARLES C. SPENGLER AND GEORGE H. SPENGLER, OF ROCKFORD, ILLINOIS.

LOCK.

SPECIFICATION forming part of Letters Patent No. 660,871, dated October 30, 1900.

Application filed July 20, 1900. Serial No. 24,267. (No model.)

To all whom it may concern:

Be it known that we, CHARLES C. SPENGLER and GEORGE H. SPENGLER, citizens of the United States, residing at Rockford, in the 5 county of Winnebago and State of Illinois, have invented certain new and useful Improvements in Mortise-Locks, of which the following is a specification.

The object of this invention is the production of a lock of the kind mentioned which shall be simple, strong, and easily and cheaply assembled.

It relates also to the process employed in producing the same.

15 In the accompanying drawings, Figure 1 is a face view of the lock assembled, the face of the case being broken away to show the bolt and the spring. Fig. 2 is a face view of the "blank" from which is formed the back piece 20 of the lock-case. Fig. 3 is a perspective view of said back piece, it being the blank shown in the preceding figure "formed up," also having the key-post inserted. Fig. 4 is the blank from which the face of the lock-case is 25 formed. Fig. 5 shows the blank illustrated in the preceding figure formed up. Fig. 6 is the blank for the lock-bolt. Fig. 7 shows the blank illustrated in the preceding figure after the next step of the operation has been 30 performed—to wit, the punching of the spring-holding opening. Fig. 8 is a view of the lock-bolt after the next step in the operation, that of inserting the spring, has been performed. Fig. 9 is a view of the lock-bolt from the op- 35 posite side thereof, the spring having been removed to show the slot in the web intended for its reception, also the portion of the web which is left to retain the spring from accidental displacement. Fig. 10 is a section 40 through the lock complete on dotted line 10 10 of Fig. 1. Fig. 11 is a fragmental edge view of the bolt, illustrating the means of securing the spring thereto.

Like letters of reference indicate corresponding parts throughout the several views.

45 In the production of this lock we provide the back piece A. (Shown in blank form in Fig. 2.) This blank is cut from sheet metal with suitable dies, the openings A' providing 50 means for securing the front or cover to the back piece A, the hole A² for receiving the

key-post A³ and the opening A⁴ for the bolt being stamped in the blank in the operation of cutting it out. After the blank A has been thus prepared the selvage A⁵ is bent at right angles to the back, as shown in Fig. 3, and the key-post A³ is riveted in its place in the opening A². The face of the lock is stamped out in the same manner from a piece of sheet metal, forming the blank B, having the double 60 keyhole B', the two projections B² on each of the opposite side edges of the blank B having the riveting-lugs B³ for entering the openings A' in the back of the lock and the opening B⁴ for the rear end of the bolt. 65

The face of the lock is formed, as shown in Fig. 5, by bending the projections B² of the blank B downward at right angles to the body of the blank.

The bolt, which is illustrated quite fully in 70 Figs. 6, 7, 8, and 9, is formed by stamping the blank C from sheet metal. This blank has the head portion C', the usual notch C² for limiting the rearward throw of the bolt, and the projection C³, upon which the fast end of 75 the spring is intended to bear. In the next operation the hole C⁴ is formed in the bolt-blank C, leaving a slight web C⁵ of material between the hole C⁴ and the edge of the blank, and the bolt is completed by driving a flat 80 spring C⁶ edgewise downward against the web C⁵, breaking the latter down and forcing the spring C⁶ into the narrow opening C⁷ thus formed in the blank C. The whole web C⁵ is 85 not destroyed, a little portion remaining on one side of the spring to hold the latter in place in the bolt C. The spring C⁶ is thus held in the slot C⁷ with its inner end in the opening C⁴, giving to the spring a particularly free movement. The strain of flexure 90 not falling upon any particular point in its length insures the long life of the spring.

In assembling the lock the spring C⁶ is driven into place as just described, breaking down the web C⁵ from the side of the bolt C 95 that will lie next to the back piece A. In right-hand locks this will be from one side of the bolt and in left-hand locks from the opposite side. The bolt C is next put in place in its opening A⁴ in the selvage A⁵ and the face B secured over it by riveting the lugs B³ on the rear side of the back piece A, the 100

rear end of the bolt C and the spring C⁶ extending outward through the opening B⁴, formed for this purpose in the face-blank B. The lock is finished and operated in the usual 5 manner.

We claim as our invention—

1. In a lock, in combination, a lock-case; a bolt; and a spring; the bolt being formed with a thin web portion adapted to be displaced by the spring when the latter is forced 10 into said web portion.

2. A bolt for locks, having an opening in its body portion formed so near its edge as to leave a thin web of material between the wall 15 of the opening and the edge of the bolt, which

web is adapted to be broken down by the forcible insertion of the lock-spring.

3. The process of securing a lock-spring to a lock-bolt, consisting of forming an opening in the bolt near the edge thereof, leaving a 20 thin web of material between the wall of the opening and the edge of the bolt, and driving the spring into said web to break the latter down and form a slot for the insertion of the spring.

CHARLES C. SPENGLER.
GEORGE H. SPENGLER.
